RAILWAY CAR CONSTRUCTION

Garth G. Gilpin, Riverside, Ill., assignor, by
mesne assignments, to Standard Railway
Equipment Manufacturing Company, a corpo-
ration of Delaware

Application August 21, 1937, Serial No. 160,209

5 Claims. (Cl. 105—404)

This invention relates to the side plate construction of a railway freight car. Heretofore, such side plate construction has usually included a rolled structural steel shape which is objectionable because of its weight and cost. The object of the present invention is to devise a new and improved sheet metal side plate that will be lighter and cheaper than the old structural steel side plate and will accomplish all of the 10 functions thereof. The invention consists in the composite sheet metal side plate and in the construction, combination and arrangements of parts hereinafter described and claimed.

In the accompanying drawing, which forms 15 part of this specification and wherein like symbols refer to like parts wherever they occur.

Fig. 1 is a vertical transverse section through the upper portion of a railway freight car provided with a side plate construction embodying 20 my invention;

Fig. 2 is a similar section on an enlarged scale through the side plate construction at one side of the car; and

Figs. 3, 4, 5 and 6 are views similar to Fig. 2 25 showing four modified forms of side plate construction.

In the accompanying drawing, my invention is shown in connection with the railway freight car comprising the usual truss side walls, each 30 of which includes side posts 1 connected at their upper ends by a side plate that forms the top chord of the truss, and a metal roof 2 that spans the car from side plate to side plate with its ends supported on and secured thereto.

35 In the construction shown in Figs. 1 and 2, the side posts of each side wall of the car are connected at their upper ends by a side plate comprising two rolled metal sheets 3 and 4 that are secured to the opposite sides of said side posts 40 and are brought together and riveted at a distance thereabove. The inner sheet 3 is a plain sheet that is preferably secured by rivets 5 to the inner faces of the side posts and extend straight thereabove. The outer sheet 4 is secured along its lower margin preferably by rivets 6 to the outer faces of the side posts and has a portion 7 that inclines inwardly and upwardly above said posts to the inner sheet 3, a vertically disposed portion 8 that is secured preferably 45 by rivets 9 to the upper marginal portion of said inner plate, and an inwardly extending upper marginal flange 10 which supports the metal roof 2. As shown in the drawing, the metal roof has a depending eaves flange 11 50 that overhangs the upper portions of the two

side plate sheets and is rigidly secured thereto by the securing rivets 9 therefor.

The modified side plate construction shown in Fig. 3 is similar to that shown in Fig. 2 except that the web 1a which connects the depending 5 outer marginal portion of the outer sheet 4a to the inwardly offset vertically disposed portion 8a thereof is disposed horizontally instead of being disposed at an inclination.

In the modified construction illustrated in 10 Fig. 4, both the inner and outer sheets 3b and 4b of the side plate converge upwardly and are riveted or otherwise rigidly secured together just below the inwardly extending roof sheet supporting upper marginal flange 10b of the outer 15 sheet 4b.

In the modified construction shown in Fig. 5, the outer sheet 4c is curved upwardly and inwardly over the side posts and the roof sheets have their eaves end portions curved to fit such 20 curvature. The inner sheet 3c is curved upwardly and outwardly over the side posts and is provided with an inturned upper marginal flange 12 that is riveted or otherwise rigidly secured to the overhanging upper portion of the 25 outer sheet.

In the modification shown in Fig. 6, the outer sheet 4d is curved inwardly and upwardly over the tops of the side posts; and the inner sheet 3d comprises a flat sheet or plate whose lower margin is secured flatwise to the inner faces of the side posts and whose upper edge abuts against the inner side of the overhanging inner marginal portion of the outer sheet and is secured thereto by a continuous weld 13.

The hereinbefore described composite sheet metal side plate has several advantages. It may be made lighter and cheaper for equal strength than the roller structural shapes heretofore used for side plates. The outer sheets of the side 40 plate may be made of galvanized or other metal that is resistant to rusting and corrosion; and the metal sheets may be readily shaped to obtain the height and clearance desired at the eaves of the car.

45 What I claim is:

1. In a railway car construction including a side wall truss having side wall posts, a side plate attached to said posts to form the top chord of said truss, and a roof secured to and supported 50 by said side plate; said side plate comprising two lightweight metal sheets extending substantially the entire length of said truss and secured along their lower margins to the respective inner and outer sides of said posts, at least the outer 55

sheet converging toward and joining the other to form said top chord as a hollow beam, and one of said sheets having at least a portion thereof shaped in conformity with the under-
5 surface of said roof and supporting said roof vertically above said side plate.

2. A side plate construction for a railway car having a sidewall truss including posts, a roof, and a side plate forming the top chord of said 10 truss and supporting said roof, said side plate comprising separate lightweight metal sheets extending substantially the entire length of said truss and having their lower margins secured to the respective inner and outer sides of said posts, 15 at least the outer of said sheets converging toward and being secured to the other sheet and to said roof vertically above said posts, and one of said sheets having its upper marginal portion extending beyond the upper marginal portion 20 of the other sheet, and being shaped in conformity with the undersurface of said roof for the further support thereof.

3. A railway car construction comprising side wall trusses with hollow side plates constituting 25 the top chords of the trusses and a roof having its eaves vertically above and supported on said side plates, each side plate comprising a pair of lightweight inner and outer metal sheets extending substantially the entire length of the respective truss secured along their lower margins to the respective inner and outer sides of side wall posts, said sheets in each pair converging upwardly above said side wall posts and secured together, the outer of said sheets extending in-

wardly beyond the upper edge of the other of said sheets to support said roof.

4. A railway car construction comprising side wall trusses with hollow side plates constituting the top chords of the trusses and a roof having 5 its eaves vertically above and supported on said side plates, each side plate comprising a pair of lightweight inner and outer metal sheets extending substantially the entire length the respective truss and secured along their lower margins to 10 the respective inner and outer sides of side wall posts, the sheets in each side plate being upwardly convergent and being secured to each other and to said roof substantially at the point of convergence vertically above said posts. 15

5. A railway car construction comprising a side wall truss with a hollow side plate constituting the top chord of the truss and a roof, each side plate consisting of a lightweight plain metal inner sheet extending substantially the entire 20 length of said truss and secured along its lower margin to the inner side of side wall posts and a coextensive lightweight metal outer sheet secured along its lower margin to the outer side of side wall posts and having a portion converging inwardly above said side wall posts and toward and secured flatwise to the upper marginal portion of said plain inner sheet and a portion that is bent inwardly over the top of said plain inner plate to support said roof, and means for 25 securing said roof to said upper marginal portion of said inner sheet.
